US00D996242S

(12) **United States Design Patent** (10) **Patent No.:** **US D996,242 S**
Lam et al. (45) **Date of Patent:** **** Aug. 22, 2023**

(54) **WEARABLE BODY TEMPERATURE MEASURING DEVICE**

(71) Applicant: **Quanta Computer Inc.**, Taoyuan (TW)

(72) Inventors: **Barry Lam**, Taoyuan (TW);
Chia-Yuan Chang, Taoyuan (TW);
Jung-Wen Chang, Taoyuan (TW);
Tung-Han Lee, Taoyuan (TW)

(73) Assignee: **QUANTA COMPUTER INC.**,
Taoyuan (TW)

(**) Term: **15 Years**

(21) Appl. No.: **29/828,358**

(22) Filed: **Feb. 25, 2022**

(30) **Foreign Application Priority Data**

Jan. 13, 2022 (TW) 111300195

(51) **LOC (14) Cl.** **10-04**

(57) **CLAIM**

The ornamental design for wearable body temperature measuring device, as shown and described.

DESCRIPTION

FIG. 1 is a front perspective view of a wearable body temperature measuring device in accordance with our new and ornamental design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

1 Claim, 7 Drawing Sheets
